UNITED STATES PATENT OFFICE.

HOSMER BLUM, OF SAN FRANCISCO, CALIFORNIA.

MIXING APPARATUS.

Application filed September 24, 1924. Serial No. 739,612.

The present invention relates to liquid mixing and aerating apparatus, and more particularly to a type of apparatus commonly termed "drink mixer". The embodiment of apparatus illustrated discloses a form designed particularly for drink mixing and counter use, for example, in connection with soda fountains and soft drink parlors. It is to be understood that the idea 10 of the invention may be so designed, arranged, and incorporated as to be capable of arrangement in many different forms.

The invention consists in a means for creating alternate suction and pressure within a liquid container by moving a body of liquid in the form of a liquid piston and specifically in utilizing a portion of the liquid in the liquid container as a fluid piston and rapidly injecting and withdrawing 20 the same from the container to cause a rapid agitation and admixture of the contents of the container; the provision of a relief valve to break or interrupt the pressure utilized to operate the liquid piston permitting the 25 piston forming liquid to drain into the container and deposit therein.

With the above mentioned and other objects in view, the invention consists in the novel construction and combination of parts 30 hereinafter described, illustrated in the accompanying drawings, and set forth in the claims hereto appended, it being understood that various changes in the form, proportion, size and minor details of construction 35 within the scope of the claims may be resorted to without departing from the spirit or sacrificing any of the advantages of the invention.

In the drawings disclosing one embodiment of the invention, Fig. 1 is a view in vertical section of the embodiment taken on line 1—1 of Fig. 3.

Fig. 2 is a transverse sectional view of the liquid reservoir taken on line 2—2 of Fig. 1 45 and Fig. 3 is a view in elevation of a battery of the mixers carried by a common base.

Referring to the several views of the drawings wherein like characters of reference designate corresponding parts, 1 indicates an elongated base upwardly from which extends one or more tubular arms 2. The lower portion of the respective arms is formed with parallel side walls 3 providing a chamber in which is mounted to reciprocate the piston 4, united through a connecting rod 5 with the crank 6 on a rotat-

ing shaft 7. The shaft is illustrated as mounting a band wheel 8 connected through a band or belt 9 with the power wheel 10 of a suitable motor 11, with the latter parts being positioned within the base 1 as illustrated. The upper end of each tubular arm 2 is curved as at 12 to overhang a portion of the base 1 and at its upper end mounts a fitting 13. The fitting comprises an up-standing flange wall 14 terminating at its lower end in an opening 15 and through said wall 14 extends a tubular channel 16, one end of which connects with the tubular arm 2 and the other end of which terminates centrally within the chamber formed by the wall 14. The fitting supports a transparent shell 17, the upper open end of which is closed by a cap 18 removably positioned thereover and depending from the cap is a concentric shield 19 extending downwardly into the upper portion of the space formed by the shell 17. A pipe 20 connects with one end of the tubular duct or conduit 16 and extends vertically within the shell 17, its upper end affording a post with which the securing nut 21 has threaded connection. The pipe 20 within the shield 19 is ported as at 22 and below the shield carries a substantially mushroom shaped baffle 23. Depending from the opening 15 is a tubular spout 24 adapted to extend into a liquid container 25 through its open top when the lower edge of the container 25 rests on the supporting arm 26 extending outwardly from the lower end of the tubular arm 2. The arm 2 near its point of attachment of the fitting is provided with a relief port 27 controlled by a valve 28 fulcrumed as at 29 and depending from the valve is an arm 30 the rear of which is adapted for positioning the rim of the liquid container 25 prior to its lower edge resting on the arm 26. The weight of the container so positioned operates the valve 28 to close the relief port 27. In the top wall of the base 1, if it is so desired, a drip sump 31 may be positioned to catch the drippings from the spout 24. As in Fig. 3, the agitators may be arranged in battery formation 105 or it may be understood that they may be erected singly. The device operates in the following manner.

The operation of the piston 4 creates an alternate suction and pressure within the arm 2, the force of which in spout 24 is relieved as long as the port 27 remains open,

The operator positions a container 25 filled with liquid to be mixed or agitated with its rim 25' in rear of the portion 30 of valve 28 and rests its lower edge on an arm 26. The weight of the liquid in the container causes a closing of the port 27 and subjects the spout 24 to the full suction and pressure action of piston 4. On the first down stroke of the piston a certain volume of liquid from the container 25 is drawn upwardly into the tube and into the shell 17 to approximately the level indicated in Fig. 1 of the drawings. This quantity of material, on successive reciprocations of the piston 4, serves as a liquid piston in its movement within the shell and within the spout 24 and thoroughly agitates and mixes the liquid within the container 25. The positioning of the port 22 connecting arm 2 with the interior of the shell 17 within the shield 19 at the upper end of the shell 17 precludes the drawing of the liquid from the shell 17 into the arm 2 and the baffle 23 precludes the splashing of the material in the shell up into the port 22. On the completion of the mixture the operator tipping the container 25 inwardly admits of the opening of the port 27. This action permits air to enter the port and the liquid from the base of the shell to quickly drain into the container.

By making the shell 17 transparent it will be understood that the color of the material in the container which is desired to be mixed may be readily seen as it is drawn into the shell and agitated therein.

I claim:

1. A liquid mixing apparatus comprising a tube for insertion at one end into a liquid container, a liquid reservoir with the base of which the other end of the tube connects, a second tube leading from the reservoir to a point near its upper end, and means for alternately creating suction and pressure within the respective tubes and reservoir.

2. A liquid mixing apparatus comprising a tube for insertion at one end into a liquid container, a reservoir with the base of which the other end of said tube connects, a second tube providing a support for the reservoir and first tube and communicating with the reservoir above the point of connection therewith of said first tube, and means for

alternately creating suction and pressure within the latter tube.

3. A liquid mixing apparatus consisting of a spout for insertion into a liquid container, a fitting with which the other end of said spout connects, a transparent shell carried by the fitting and providing a reservoir, a lateral port in the fitting, a tube connected with one end thereof and extending upwardly into the shell, said port affording a communication between its interior and the interior of the shell, a tubular support communicating with the other end of the port of said fitting, and means for creating alternate suction and pressure within said support.

4. A mixing apparatus comprising a base, a tubular support carried thereby and provided on its interior with a pump chamber, a pump piston mounted therein, means for operating the pump piston to create alternate suction and pressure in said support, a reservoir carried by and connecting with the tubular support, and a spout depending from the reservoir and communicating at one end therewith and at a point below the point of connection of said support.

5. A portable mixing apparatus comprising a base, a tube extending upwardly therefrom providing a support and having a depending terminal portion for reception at one end in a liquid container, means within the base and cooperating with the first tube for alternately creating suction and pressure within the tube, said tube formed within its length with a vent, and means actuated by a receptacle positioned to receive the depending portion of the tube for closing said vent.

6. A mixing tube comprising a base, a tube extending upwardly therefrom providing a support and having a depending terminal portion for reception at one end in a liquid container, means cooperating with the first tube for alternately creating suction and pressure within the tube, said tube provided within its length with a vent, and means actuated by a receptacle positioned to receive the depending portion of the tube for closing said vent.

In testimony whereof I have signed my name to this specification.

HOSMER BLUM.
